1850.

Fig. 330

William Ballard of New York N. Y.
Letters Patent. No. 330. Dated Oct. 29. 1850.

The Schedule referred to in these Letters Patent and making part of the same.

To all whom it may concern:

Be it known that I, William Ballard of the City, County and State of New York, have invented or produced a new and ornamental design, for cast iron railings or fences, for Cemetery's, or other places, and I do hereby declare that the following is a full and exact description of the same.

The design of my invention is to make a railing of iron or other suitable metal in which castings are made, for burial plots in Cemetery's, and for this purpose, and to make it conform to the picturesque and rural character of such places; and at the same time to attain durability, I have designed a fence, composed of lengths of fencing, and posts, for supporting it, to represent as near as practicable the branches and stems of young trees, and resting upon a base, designed of the grape vine and leaves and clusters of grape.

To do this, I have designed my gate, and intermediate posts (A' and A²) to represent the stems of young trees, having their branches trimmed off, so as to give a knarled appearance, and ornamental contrast, as well as appearance of strength to the stems or branches B. B. &c, composing fencing or railing.

These stems or branches, have their young shoots, so clipped or trimmed, as to present an appearance of interlacing of them, and of such various shapes and angles, as to give a constant variety of effect, as well as pleasing rural aspect.

Underneath these branches a double rail, or margin or base, is formed, and throughout its entire length is extended a wavy line of the grape vine, having alternately a leaf, and cluster of grape.

All these parts are in one general design, and are moulded and cast at one time, the upper and lower rails having their ends projecting beyond the stems or branches sufficiently, to admit of bolting to the supports on the posts, and to complete the entire design of my Cemetery or rural iron railing.

What I claim is the particular ornamental design or device for a railing and gate posts, as herein combined, and specified; that is, the posts, panel and

marginal grape vine base in form and design substantially and herein set forth.

Witnesses.
